(57) **CLAIM**

The ornamental design for a digital license plate frame, as shown and described.

DESCRIPTION

FIG. 1 is a front, top, and left side perspective view of a first embodiment of a digital license plate frame, which embodies our design.

FIG. 2 is a rear, bottom, and left side perspective view thereof.

FIG. 3 is a front view thereof.

FIG. 4 is a rear view thereof.

FIG. 5 is a right side view thereof.

FIG. 6 is a left side view thereof.

FIG. 7 is a top view thereof.

FIG. 8 is a bottom view thereof.

FIG. 9 is a front, top, and left side perspective view of a second embodiment of a digital license plate frame, which embodies our design.

FIG. 10 is a rear, bottom, and left side perspective view thereof.

FIG. 11 is a front view thereof.

FIG. 12 is a rear view thereof.

FIG. 13 is a right side view thereof.

FIG. 14 is a left side view thereof.

FIG. 15 is a top view thereof; and,

FIG. 16 is a bottom view thereof.

The second embodiment of the digital license plate frame in FIGS. 9-16 includes symbolic break lines. The appearance of the digital license plate frame between the break lines forms no part of the claimed design.

Although the illustrated license plate frame can be used with digital license plates, Applicant contemplates that it could also be used with conventional license plates and reserves the right to amend the Title to refer simply to a license plate frame.

1 Claim, 12 Drawing Sheets
